Allen & Allen

UNITED STATES PATENT OFFICE

LEWIS M. CROSLEY, OF CINCINNATI, OHIO, ASSIGNOR TO THE CROSLEY RADIO CORPORATION, OF CINCINNATI, OHIO, A CORPORATION OF OHIO

REFRIGERATION DEVICE

Application filed November 19, 1928. Serial No. 320,313.

My invention relates to portable refrigeration units of the general type shown and described in application for Letters Patent of D. F. Keith, Ser. No. 201,904, filed June 27, 5 1927. In this type of device there are two receivers or balls, one of which serves as a generator absorber and the other of which serves as a condenser evaporator. Intermediate the two balls is a conduit which serves to connect them and also to support the structure during 10 its use. Within this conduit are located the various necessary parts serving to separate the path of the refrigerant to and from the generator absorber.

15 It is my object to simplify and increase the reliability of action of the device shown in the application for patent to Keith above mentioned and particularly to facilitate the draining of the condenser evaporator and to provide against sudden surges set up by pressure 20 in the device from breaking the seal which disassociates the inflow and outflow from the generator absorber. These objects and other advantages to be noted I accomplish by that 25 certain construction and arrangement of parts of which a typical example is shown and described and the novelty of which will be set forth in the claims.

In the drawings:
30 Figure 1 is a central vertical section through the device.

Figure 2 is a detail of the valve.
Figure 3 is a perspective of the baffle.
As has been stated the particular mechanism to which I have applied my improvements is the design evolved by D. F. Keith in his aforesaid application for Letters Patent. My invention is however, applicable to a variety of designs and I have shown it applied 40 to the Keith device because it is of familiar type and very widely used. The device illustrated has a generator absorber ball 1, a condenser evaporator ball 2, and a connection conduit 3. The conduit extends at the condenser evaporator end beyond the port from the condenser evaporator as shown at 4 to provide a sump. The condenser evaporator is secured to the conduit and has a tube 6 extending well into the conduit. A baffle formed of 45 50 a zigzag metal strip 7 is housed within the

conduit just above the tube 6. This baffle acts as a dehydrator since the vapors from the generator absorber will traverse the zigzag plate and drops of moisture will collect thereon and fall into the sump without entering the tube 6. Inserted in the horizontal portion of the conduit close to where it bends down to the condenser evaporator is inserted a plate 8 which acts as a dam in a manner which will be described. A carrying handle 9 is mounted 55 on the conduit and has a foot 10 secured thereto and on which the device rests when it is in draining position.

The vertical portion 11 of the conduit is connected to the generator absorber shell and within this portion of the conduit a liquid seal is established, the level of which is indicated at 12, which level is desired by the upper end of the tube 13 which acts during the absorption cycle of the device.

Set into the top of the generator absorber ball is a tube 14 which terminates below the level of the seal. An annular channel shaped housing is secured over the upper end of the tube 14 and resting on top of the tube is a valve plate 16 which is larger than the opening 17 in the housing.

As so constructed the operation of the device is as follows: Considering the generator absorber as filled with a suitable absorbent 80 and the end of the pipe 13 fully submerged therein, the condenser evaporator shell is placed in a cooling medium and heat applied to the generator absorber shell. This results in evaporating the refrigerant, such as for example, ammonia gas with which the absorbent is saturated, the said vapor passing up through the tube 14, forcing up the valve plate 16 and escaping through the liquid seal 12 into the conduit. The vapors pass through the conduit, flowing over the valve 8 and baffle 7, and passing into the condenser evaporator through the pipe 6. This is continued until the refrigerant has been largely driven off from the generator absorber and sufficient 85 pressure built up in the condenser evaporator to cause the vapors of the refrigerant to condense, in the presence of the heat absorbing medium in which the condenser evaporator is 90 submerged.

As soon as the heat is discontinued and the temperature drops in the generator absorber, the liquid refrigerant will start to evaporate resulting in a large absorption of heat. The 5 gases will flow through the tube 18 and down into the absorbent in the generator absorber into which absorbent they will become dissolved.

The liquid seal 12 prevents the gases from 10 flowing into the generator absorber through the tube 14 and if by accident there should be insufficient liquid in the seal, or if a sudden surge of pressure should develop during either cycle of the device, the valve 16 will 15 prevent the refrigerant gas from passing into the generator absorber through the tube 14. The pressure present in the conduit and the static head of the liquid seal itself will keep the valve 16 closed down against the tube 14 20 except during the generation step which has been described.

After the refrigerant has evaporated and there is equal pressure within the generator absorber, and within the conduit, the device is 25 again applied to a source of heat to regenerate the system. Prior to this the system should be drained of all liquid which is done by inverting the structure permitting it to rest on the generator absorber ball 1 and the foot 30 10. Due to the large opening in the tube 6, and the freedom for passage of liquid past the baffle and through the conduit, a very short interval will result in a complete drainage of the absorbent from all parts of the 35 system beyond the dam 8. The device is then righted and the liquid within the conduit 3 will flow into the generator absorber through the tube 18 and will not flow back into the sump 4 because of the presence of the dam 8. 40 Sufficient of the liquid will collect in the portion 11 of the conduit to reestablish the liquid seal 12.

It is apparent that my improvements are applicable to other than ball shaped receivers 45 and that with obvious modifications, they can be applied to a variety of refrigeration devices of the absorption type.

Having thus described my invention what I claim as new and desire to secure by Letters 50 Patent, is:—

1. In an absorption system refrigeration device the combination of a generator-absorber chamber, a condenser-evaporator chamber, a conduit between them, means for establishing a liquid seal between the interior of the conduit and the generator-absorber chamber, a passageway from the generator-absorber chamber terminating at a point below the level of said seal, and a valve for said 55 passageway.

2. In an absorption system refrigeration device the combination of a generator-absorber chamber, a condenser-evaporator chamber, a conduit between them, means for establishing a liquid seal between the interior 60

of the conduit and the generator-absorber chamber, a passageway from the generator-absorber chamber terminating at a point below the level of said seal, and a valve for said passageway, said valve applied to the terminus of the passageway and acting as a check valve under the static head of the liquid seal. 70

3. In an absorption system refrigeration device the combination of a generator-absorber chamber, a condenser-evaporator chamber, a conduit between them, means for establishing a liquid seal between the interior of the conduit and the generator-absorber chamber, a passageway from the generator-absorber chamber terminating at a point below the level of said seal, and a valve for said passageway, said valve formed as a disc placed over the end of the passageway below the level of the liquid seal, a housing around the disc to hold it against moving out of position, as and for the purpose described. 75

4. In an absorption system refrigeration device the combination of a generator-absorber, a condenser-evaporator and a conduit between them, of a dehydration baffle formed of a zig-zag strip of metal set into the conduit above the generator-absorber connection with said conduit, and means for collecting deposited moisture from said baffle at a point beyond the point of connection of the generator-absorber. 80

5. In an absorption system refrigeration device the combination of a casing forming a generator-absorber, a casing forming a condenser-evaporator, a conduit between them, a port from the condenser-evaporator thereinto, and ports from the generator-absorber thereinto, and a dam located in the conduit at a position to lie above the liquid level maintained when daining the condenser-evaporator by inverting the position of the structure, whereby the movement of liquid back into the condenser-evaporator upon righting the structure is prevented, said structure provided with means for supporting it upon a desired level surface in a position to define the proper inverted position thereof for draining. 100

6. In a device of the character described, including two vessels and a conduit extending up from one vessel, then crossing over, and then extending down to the upper part of the other vessel, a dam in the crossing-over part of said conduit, and a baffle in the downwardly extending part of said conduit having a shape defining a sinuous path through said downwardly extending part of said conduit. 110
